UNITED STATES PATENT OFFICE

LOUIS G. PAUL-ANTONIO, OF TILTONSVILLE, OHIO

FRAME FOR DOORS, WINDOWS, AND THE LIKE

Application filed March 9, 1928. Serial No. 260,391.

The present invention relates to frames for doors, windows and the like and has for its prime object the provision of a frame structure which may be manufactured in different sizes and furnished to a builder for ready assembly in wall openings.

Another very important object of the invention resides in the provision of a frame structure of this nature with means whereby it may be assembled in the opening in a firm tight manner and so as to compensate for any irregularities in the opening.

Another very important feature of the invention resides in the provision of a frame wherein the sections thereof are assembled together in a strong and rigid manner.

A still further very important object of the invention resides in the provision of a frame of this nature which is exceedingly simple in its construction, inexpensive to manufacture, strong and durable, compact and convenient, easy to manipulate, thoroughly efficient and reliable for the purpose intended and otherwise well adapted to attain the features of advantage desired.

With the above and numerous other objects in view as will appear as the description proceeds, the invention resides in certain novel features of construction, and in the combination and arrangement of parts as will be hereinafter more fully described and claimed.

In the drawings:

Figure 1 is an elevation of a frame embodying the features of my invention showing the same in a wall with a door mounted in place,

Figure 2 is an enlarged detail elevation of one of the upper corners of the frame structure showing the casing board removed,

Figure 3 is an enlarged detail vertical section taken substantially on the line 3-3 of Figure 1,

Figure 4 is an enlarged detail horizontal section taken substantially on the line 4-4 of Figure 1, and

Figure 5 is a fragmentary detail perspective view of the molding.

In order to illustrate and explain the utility and advantages of my invention I have

selected merely by way of example a door frame and it will readily appear that the same principles may be used in a window frame and the like.

The numeral 5 denotes a jamb board and the numeral 6 another jamb board disposed in spaced parallelism thereto. The numerals 7 denote two casing boards. These boards 5, 6 and 7 make up a box like side vertical rail of the door frame. Of course there are two of these side rails of box like formation which have extended across their top a head which includes jamb boards 5' and 6' and casing boards 7'. A bracer 8 is disposed between the jamb boards 5 and 6 along the median longitudinal dimensions thereof. As will be apparent from an inspection of Figure 2 the jamb board 6' has a notch 10 formed therein to receive the upper end of the jamb board 6 while the jamb board 5 has a notch 11 therein to receive the end of the jamb board 6'. The jamb board 5' is provided with a notch 12 to receive the upper edge of the jamb board 5.

The casing boards 7 and 7' are nailed to the longitudinal edges of the jamb board as indicated to advantage in Figure 3. It will be noted by referring to Figure 3 that the extremities of the jamb boards 7' are reduced in thickness while the upper extremities of the jamb boards 7 are reduced in thickness so that these ends may be disposed in overlapped superimposed relationship and nails 14 may be driven therethrough and in the jamb board 6'.

The frame thus far described would be manufactured in different sizes to approximately fit wall openings. The frames would be slightly smaller than the wall openings as is indicated to advantage in Figures 3 and 4 so as to leave spaces between the jamb boards 5 and 5' and the opening edge of the wall. In order to cover this opening and finish the job off in proper manner and also for the purpose of holding the door frame rigidly in place in a strong and durable manner to have all the advantages of the ordinary built in door frame I provide molding strips denoted generally by the letters M.

Each strip comprises a body 15 of elong-

gated solid construction having an inner flat face 16 to rest up against the edges of the jambs 5 and 5'. A flange 17 projects from one longitudinal edge of the face 16 and 5 is beveled off as indicated at 18 so that this flange may be scribed off along the line 19 to be flat against the wall. Thus unevenness in the plaster may be compensated for.

The edge 20 remote from the flange 17 is flat 10 and disposed perpendicular to the face 16 and adjacent the outer face 21 is provided with a longitudinally extending tongue 22 for engaging over the casing boards 7 and 7' and through which nails 23 may be driven which 15 are also driven through the casing board and into jambs 5 and 5'. The outer face of the molding strip 21 may have any desired fanciful, decorative or artistic curvatures.

The edge adjacent the flange 17 is disposed 20 in parallelism with the edge 20.

From the above detailed description of the example of my invention illustrated in the accompanying drawing it will be seen that the frame may be manufactured for the 25 purpose of being sold complete and shipped from the factory complete to the builder so that they may be assembled in the wall openings in a rigid, strong and firm manner. The rails and heads are built up in 30 box like manner so that all the members are held in place firmly and rigidly and so that the joints are tight whereby the frame may be mounted in position to withstand the ordinary usages of a door frame and to withstand 35 the rather hard usage to which the frame would be subjected during transit and in loading and unloading.

The joints provided in the specific manner described will not easily open up and will 40 withstand the usages explained above. In the header the braces strengthen the box like structure making the same rigid and secure, the jamb boards 5 and 5' also function as braces when the frame is in the wall opening. 45 The molding described is in the form of a band. This molding is provided to cover the gap or play space between the frame and the edge of the wall opening so as to make a neat finished job in membering the frame 50 with the plaster wall opening or the like.

It is thought that the construction, utility and advantages of this claimed structure will now be clearly understood by those skilled in this art without a more detailed 55 description thereof.

The present embodiment of the invention has been disclosed merely for the purpose of exemplification since in actual practice it attains the features of advantage enumerated 60 as desirable in the statement of the invention and the above description.

It will be apparent that changes in the details of construction, and in the combination and arrangement of parts may be resorted to 65 without departing from the spirit or scope

of the invention as hereinafter claimed or sacrificing any of its advantages.

Having thus described my invention what I claim as new is:

A frame structure of the class described 70 comprising a plurality of interconnected box like frame members, each frame member comprising an outer jamb board, an inner jamb board disposed in spaced parallelism thereto, a pair of casing boards fixed to the 75 edges of the jamb board, and molding strips having flat inner faces to rest against the edges of the outer jamb boards and flat edges to rest against the outer edges of the casing board and tongues to overlap a portion of 80 the outer faces of the casing board, and flanges projecting inwardly to engage the wall and being beveled so that they may be scribed to fit flush against the wall.

In testimony whereof I affix my signature. 85
LOUIS G. PAUL-ANTONIO.
